(57) **CLAIM**

The ornamental design for an earphone case, as shown and described.

DESCRIPTION

FIG. 1 is a front view of an earphone case showing the new design;

FIG. 2 is a back view thereof;

FIG. 3 is a left-side view thereof;

FIG. 4 is a right-side view thereof;

FIG. 5 is a top view thereof;

FIG. 6 is a bottom view thereof;

FIG. 7 is a front, right-side perspective view thereof;

FIG. 8 is a perspective view of changing state thereof; and,

FIG. 9 is a perspective view of using state thereof.

The broken lines shown in the drawings depict environmental subject matter and form no part of the claimed design.

1 Claim, 9 Drawing Sheets
